UNITED STATES PATENT OFFICE.

HENRI AUGUSTUS GUILLEY, OF EASTON, PENNSYLVANIA, ASSIGNEE TO INGERSOLL-RAND COMPANY, OF JERSEY CITY, NEW JERSEY, A CORPORATION OF NEW JERSEY.

ROTATION FOR ROCK DRILLS.

Application filed May 26, 1921. Serial No. 472,823.

To all whom it may concern:

Be it known that I, HENRI AUGUSTUS GUILLEY, a citizen of the United States, and a resident of Easton, county of Northampton, and State of Pennsylvania, have invented a certain Rotation for Rock Drills, of which the following is a specification.

This invention relates to rotation motors for fluid actuated rock drills but more particularly to independent rotation for rock drills of the hammer type.

The objects of the invention are to enable the power of the rotation to be increased when required by means of one or more auxiliary motors adapted to operate simultaneously with the main rotation motor as desired.

Another object is to secure automatic means for supplying motive fluid to the auxiliary motor or motors when the pressure in the main motor builds up beyond a predetermined point, thus automatically assisting the main motor when needed.

The invention is shown in one of its preferred forms in the accompanying drawings in which:—

Figure 1 is a top plan view of a rock drill partly broken away and partly in horizontal section showing so much of the operative parts of the machine as will serve to illustrate the invention;

Figure 2 is a diagrammatic transverse sectional view of Figure 1 taken through the main motor on the line 2—2 looking in the direction of the arrows;

Figure 3 is a similar view taken through one of the auxiliary motors on the line 3—3 of Figure 1 looking in the direction of the arrows, and

Figure 4 is a similar view taken through a second auxiliary motor on the line 4—4 of Figure 1 looking in the direction of the arrows.

Referring to the drawings, Figure 1 illustrates so much of the principal parts of a fluid actuated rock drill of the hammer type as relate to the independent means constructed in accordance with the invention for rotating the drill steel.

The cylinder A is adapted to receive a reciprocating hammer piston for imparting blows of impact to the rotating drill steel B, carried in the rotation sleeve or chuck C in the front head D. A back cylinder

portion E provides a motor casing closed by a back head F, and the cylinder A, front head D, back cylinder portion E and back head F may be held together in the usual manner as by means of the side bolts G.

Rotation is imparted to the drill steel B by means of a series of fluid actuated rotation motors, of which the motor H may be considered the main motor, and the motors J and K as auxiliary motors. These motors are preferably all of the gear type for imparting continuous rotary motion to the drill steel and in this instance pairs of gears in the train of gearing between the main motor H and the drill steel conveniently constitute the auxiliary motors J and K, and are supplied with motive fluid by suitable ports and passages, although the auxiliary motors obviously need not necessarily be a part of the gear train itself.

The main motor mounted in the back cylinder portion E, comprises the gears L and O on the spindles P and Q, and motive fluid is supplied through the passage R and exhausted from the port S. The gear spindle Q is provided with the pinion T meshing with the gear U on the shaft V extending through the cylinder casing to the front end of the machine and carrying the pinion W meshing with the gear X on the rotating chuck C.

The pinion T and gear U in the back cylinder portion E together form the auxiliary motor J to which motive fluid is supplied through the passage Y forming a branch from the main supply passage R, and the pinion W and gear X in the front head D together form the auxiliary motor K to which motive fluid is supplied through the passage Z conveniently forming a branch from the auxiliary passage Y. The motor J exhausts through the port a and the motor K exhausts through the port b.

The main motor H is powerful enough to rotate the drill steel under ordinary conditions, and the auxiliary motors are adapted to assist the main motor when needed. Means are preferably provided for automatically bringing the auxiliary motors into action successively, so that motive fluid is supplied to each succeeding motor in the series when the pressure in a preceding motor builds up beyond a predetermined amount. For this purpose, automatic spring pressed

valves *c* and *d* are provided in the branch passages *Y* and *Z* respectively, and subjected to the pressure in the motors *H* and *J* respectively through the ports *e* and *f* leading to the motor casings.

When the pressure in the main motor *H* reaches a predetermined point, the valve *c*, which normally closes the branch passage *Y* will open said passage and admit motive fluid to the auxiliary motor *J*, and at a predetermined pressure in motor *J*, the valve *d* will open and admit motive fluid to auxiliary motor *K*. When the resistance to rotation again decreases, the valves *c* and *d* will automatically close and normal rotation will be resumed.

I claim:

1. In a fluid actuated rock drill of the hammer type, the combination of a percussive element, and an automatic independent drill steel rotating element comprising a main fluid actuated rotary gear motor, a rotating chuck into which the drill steel is adapted to extend, a train of pairs of rotary driving gears constantly rotating in series relation between the main motor and the rotating chuck, supply and exhaust ports for each pair of associated driving gears, any pair of associated driving gears being thereby capable of constituting an auxiliary motor for assisting rotation by the application of fluid pressure between the gears of said pair, means for supplying motive fluid to the main motor and controlled means for supplying motive fluid to an auxiliary motor in addition to the main motor.

2. In a fluid actuated rock drill of the hammer type, the combination of a percussive element, and an automatic independent

drill steel rotating element comprising a main fluid actuated rotary gear motor, a rotating chuck into which the drill steel is adapted to extend, a train of pairs of rotary driving gears constantly rotating in series relation between the main motor and the rotating chuck, supply and exhaust ports for each pair of associated driving gears, any pair of associated driving gears being thereby capable of constituting an auxiliary motor for assisting rotation by the application of fluid pressure between the gears of said pair, and automatic means for supplying motive fluid to the auxiliary motor when pressure in the main rotary gear motor builds up beyond a predetermined point.

3. In a fluid actuated rock drill of the hammer type, the combination of a percussive element, and an automatic independent drill steel rotating element comprising a main fluid actuated rotary gear motor, a rotating chuck into which the drill steel is adapted to extend, a train of pairs of rotary driving gears constantly rotating in series relation between the main motor and the rotating chuck, supply and exhaust ports for the main motor and for each pair of associated driving gears, any pair of associated driving gears being thereby capable of constituting an auxiliary motor for assisting rotation by the application of fluid pressure between the gears of said pair, and automatic fluid actuated valves for supplying motive fluid to each succeeding motor in the series, when pressure in a receding motor builds up beyond a predetermined point.

In testimony whereof I have signed this specification.

HENRI AUGUSTUS GUILEY.
